INVENTOR

N. Z. Lind
ATTORNEY

UNITED STATES PATENT OFFICE.

WILLIAM ROBERTSON, OF ERIE, PENNSYLVANIA, ASSIGNOR TO LOVELL MANUFACTURING COMPANY, OF ERIE, PENNSYLVANIA, A CORPORATION OF PENNSYLVANIA.

WRINGER.

Application filed August 2, 1921. Serial No. 489,174.

To all whom it may concern:

Be it known that I, WILLIAM ROBERTSON, a citizen of the United States, residing at Erie, in the county of Erie and State of Pennsylvania, have invented new and useful Improvements in Wringers, of which the following is a specification.

For many purposes it is desirable to form the wringer frame with as little height as possible. One of the purposes of this invention is to provide a wringer with a pressure mechanism giving the rolls a wide expansion and at the same time forming a comparatively low frame. Other details of the invention will appear from the specification and claims.

The invention is illustrated in the accompanying drawings as follows:—

Fig. 1 shows a front elevation of the wringer.

Fig. 2 an end elevation of the wringer.

Fig. 3 a section on the line 3—3 in Fig. 2.

Fig. 4 a section on the line 4—4 in Fig. 2.

Fig. 5 an enlarged view of one of the wringer stiles.

Fig. 6 a top view of one end of the wringer frame.

1 and 2 mark the rolls. These are carried by bearings 3 and 4 respectively, the bearings being mounted in a guide groove 5 formed in the walls of the guide slot 6 of the stiles 7. The stiles are formed preferably of cast metal. Cross bars 8 extend across the wringer from stile to stile at a point opposite the lower roll and tie rods 9 extend across the top of the wringer, the rods extending through the perforated ears 7^a on the stiles, the rods being provided with shoulders 9^a engaging the inner ear and a nut 9^b on the outer end clamping the ends of the rods to each stile. A plate 9^c extends across each stile bridging the guide slot, the rods 9 extending through this plate and the nuts clamping the plate in place. A top bar 10 extends across the top of the wringer, it having the seats 11 resting on the top bearing 3. The top bar is separated intermediate its ends and hinged at 12. One part of the top has a shoulder 13 operating in connection with a latch 14 on the other part normally locking the sections of the top bar in alignment.

A pressure mechanism is formed as fol-

lows: Levers 15 are pivoted at 16 on the brackets 17, the brackets extending from the sides of the frame in two arms, one on each side of the lever 15. One end 18 of the lever which is of bell-crank form rests on the top bar 10. A spring 19 extends outwardly from the face of the wringer frame to the lower arm 20 of the lever and pressing the lower arm outwardly presses the top arm downwardly on the top bar exerting pressure on the rolls. A screw 21 extends through the lever against the spring so that the tension may be varied.

The lever 15 is arranged on the top bar slightly out of position vertically above the point of engagement of the bearing 3 with the top bar. As a consequence when the latch 14 is released from the shoulder 13 the top sections of the top bar swing upwardly at the hinge breaking the connection between the end of the lever and the bearing and consequently releasing the pressure on the rolls.

With this construction a comparatively low wringer frame may be provided. At the same time a spring of sufficient length is formed to give the pressure mechanism the desirable range.

What I claim as new is:—

1. In a wringer, the combination of a frame; rolls mounted in the frame; pressure mechanism for the rolls comprising a spring extending outwardly from a plane through the axes of the rolls, and a lever pivotally mounted on the frame having one end subjected to the action of the spring; and means communicating the pressure from the opposite end of the lever to the rolls comprising a release device adapted to break the communication between the lever and the rolls and release the rolls from the pressure of the spring.

2. In a wringer, the combination of a frame comprising stiles; rolls mounted in the stiles, the upper roll being slidingly mounted; brackets extending from the stiles; bell crank levers pivotally mounted in the brackets; springs extending outwardly from the frame operating on one end of the bell crank levers; and means communicating the pressure of the opposite end of the bell crank levers to the upper roll comprising a release device adapted to break

the communication between the lever and the roll for releasing the roll from the pressure of the spring.

3. In a wringer, the combination of a frame; rolls mounted in the frame; pressure mechanism for the rolls comprising a spring extending outwardly from a plane through the axes of the rolls, and a lever communicating pressure from the spring to the

rolls; and a release device between the spring and rolls for releasing the rolls, said release device comprising a top bar arranged between the rolls and the lever, said top bar being transversely breakable.

In testimony whereof I have hereunto set my hand.

WILLIAM ROBERTSON.
